(57) **CLAIM**

The ornamental design for a ceiling fan motor housing and light kit as shown and described.

DESCRIPTION

FIG. 1 is a top perspective view of a ceiling fan motor housing and light kit, showing our new design in a ceiling fan environment.

FIG. 2 is a bottom perspective view thereof;

FIG. 3 is a top view thereof with the ceiling fan environment removed to show aspects of the design that are not visible when combined;

FIG. 4 is a bottom view thereof;

FIG. 5 is a front view thereof;

FIG. 6 is a rear view thereof;

FIG. 7 is a right-side view thereof; and,

FIG. 8 is a left-side view thereof.

Portions of the ceiling fan environment and the ceiling fan motor housing and light are shown in broken lines. Portions shown in broken lines form no part of the claimed design. The ceiling fan blades are shown with jagged broken lines with the portion of the blades between the jagged broken lines forming no part of the claimed design.
